EX

OR D 19,797

UNITED STATES PATENT OFFICE.

FRANKLIN L. SHEPPARD, OF PHILADELPHIA, PENNSYLVANIA, AND FRANCIS RITCHIE, OF TROY, NEW YORK, ASSIGNORS TO ISAAC A. SHEPPARD, FRANKLIN L. SHEPPARD, AND HOWARD R. SHEPPARD, OF PHILADELPHIA, PENNSYLVANIA.

DESIGN FOR A RANGE OR STOVE.

SPECIFICATION forming part of Design No. 19,797, dated April 29, 1890.

Application filed March 11, 1890. Serial No. 343,528. Term of patent 7 years.

To all whom it may concern:

Be it known that we, FRANKLIN L. SHEPPARD, of Philadelphia, Pennsylvania, and a citizen of the United States, and FRANCIS 5 RITCHIE, also a citizen of the United States, residing in Troy, New York, have invented a new and original Design for a Range or Stove, of which the following is a specification.

Our design for the ornamentation of the 10 plates of a range is fully illustrated in the accompanying photographic representation.

The general design is that of foliated and scroll work, and the leading feature is the leaf surrounded by a circular band.

15 The ornamentation of the base-panels is composed of a central representation of a leaf with a circular band surrounding the same, the two ends of which are tied at the base. Projecting from each side of this band is ornamental scroll-work. The panel is surrounded by a ribbed border.

20 The ornamentation of the doors of the range is in keeping with the ornamentation of the base-panels, the oven-door A having a central name-plate *b*, which is ornamented in keeping with other parts of the stove. On each side of this ornamental panel is scroll-work with a central foliated design, the band being broken, showing flaring ends. The fire-

25 door B has central ornamentation composed of the leaf and circular band and a short scroll at each side of the knot in said band. The ash-pit door and ventilator have small foliated scroll designs thereon, as clearly 30 shown. The oven-door A is bounded by a ribbed band.

The deflecting-plate D under the boiler is divided into two panels, each panel having the central leaf representation, the circular band and the scrolls projecting from each 40 side similar to the base-panel *a*. The side panels of the range are in keeping with the front panel, and the open-work of the supporting structure is also in keeping.

We claim—

- 45 1. The design for a range, as herein shown and described.
2. In the design for a range, the design for a panel, as herein shown and described.
3. In the design for a range, the design for 50 the oven-door, as herein shown and described.
4. In the design for a range, the design for the fire-door, as herein shown and described.
5. In the design for a range, the design for 55 the deflecting-plate, as herein shown and described.

In testimony whereof we have signed our names to this specification in the presence of two subscribing witnesses.

FRANKLIN L. SHEPPARD.
FRANCIS RITCHIE.

Witnesses to the signature of Franklin L. Sheppard:
